ABSTRACT OF THE DISCLOSURE

In an apparatus for winding strands in two directions around an advancing core, instead of passing through a die, the strands approaching the core are deflected over the outer surface of a ring or plate and pass over each other on this surface.

BACKGROUND OF THE INVENTION

It has long been known to apply winding in two directions, that is, both left hand and right hand, around a core, such as an electric cable, hose, or tensile strand, to cite common examples. In some cases, such as braids the strands are interlocked, passing alternately over and under each other, in other cases, where more flexibility is required, the strands are not braided, but some are applied left hand and some right hand, without interlocking. In a braiding machine, which can also be used to apply the non-interlocking windings, strand supply spools are mounted on two supports that rotate around the advancing core one clockwise, and one counterclockwise. A die or ring is mounted downstream of the spools, encircling the core, and the strands all pass within this die. This known structure works well for close winds or braids but for very open application where the advance of the core is relatively great for each revolution of the strands the known apparatus has resulted in uneven winding and has imposed a limitation on the positioning of the strand guides since these had, perforce, to be located outside the circumference of the ring.

SUMMARY

I have found that a very even open winding or braid can be applied by passing the strands over the outside surface of an annulus and that, surprisingly, the strands will encounter and pass over each other evenly on this surface. My apparatus for winding a plurality of strands left hand and an additional plurality of strands right hand around an advancing core comprises a means advancing the core from a supply thereof, first means supporting a first plurality of supply means of strands and means for rotating said support means left-hand around the core. It also comprises second means supporting a second plurality of supply means of strands and means for rotating this second support means right-hand around the core. My apparatus comprises as an essential feature, an annular member comprising an outer surface in a circle normal to the axis of advance of the core, and also comprises guide means, mounted upstream of the annular member, for the strands. By suitable means the rotating means and the advancing means are synchronized so that each strand rides on the surface of the annular member at a point between the guide means and the core and the strands encounter each other and pass over each other on that surface. In one embodiment of my invention all the strands rotating in one direction may pass over all those that rotate in the opposite direction and in another embodiment at least one strand may pass under the strands rotating in the opposite direction.

2

BRIEF DESCRIPTION OF THE DRAWING

In the drawing the figure shows a side view of an apparatus of my invention.

5 DETAILED DESCRIPTION OF PREFERRED EMBODIMENT

In the figure the apparatus, indicated generally by the numeral 10 is used to wind a plurality of strands 11—11 in one direction so as to make a left-hand wind, and another plurality of strands 12—12 in the opposite direction to make a right-hand wind around a core 13 advancing from a reel 14 over a guide sheave 16. The strands 12 are supplied from cops or spools 17 mounted on turntable 18 and the strands 11 are supplied from cops 19 mounted on a lower coaxial turntable 21. The turntable 21 rotates in a bearing 22 mounted on a fixed frame 23. A sprocket 24 fixed to the turntable 21 is driven by a chain 26 from sprocket 27 on a vertical shaft 28 which, in turn, is driven by means of a chain 29 by a power source, not shown. The turntable 18 is mounted on a shaft 31 passing freely through a central opening in the turntable 21, sprocket 24, and bearing 22. The turntable 18 is supported by a conventional thrust bearing (not shown) in the frame 22 and terminates in a sprocket 32 whence it is driven by the chain 33 sprocket 34 and gears 36, 37 in a direction opposite to the direction of rotation of the turntable 21. The core 13 passes through a tubular support 38 which is surmounted by a annular disk 39 having a smooth circular surface 41. The support 38 and disk 39 do not rotate. The core 13 is advanced by a capstan 42 whence it passes over a guide sheave 43 to a take-up reel, not shown. The speed of the core 13 is determined by the speed of the capstan 42 which is driven by means of worm gearing 44 from the shaft 28 by means of the chain 46 selected for any desired ratio to the rotation of the turntables 18, 21. As the turntables rotate they wind the strands 11, 12, in opposite directions around the core 13 with the strands 11 covering the strands 12. The strands 11 are passed through eyelets 47, 48 mounted on the turntable and the strands 12 are passed through eyelets 49 on the turntable 18. The eyelets 48, 49 are so positioned that, in their path to the core 13, which they all reach at the same point of application 51 the strands "break" on the surface 41, each of the strands forming an angle, alpha, between the edge of the disk 39 and the core 13 which is determined by the ratio of the disk diameter to the core diameter and the ratio of the speed of the capstan 42 to the rotation of the turntables. Tensioning devices 52 of known construction apply tension to the strands 11 and 12, as desired, and as each of the tensioned strands 11 encounter one of the strands 12 on the surface 41 it passes over the strand on this surface in a surprisingly uniform manner to form a uniform, even spacing of the strands around the core. In my apparatus so far described all of the strands 11 rotating in one direction are applied over all of the strands 12 of the opposite hand. However by adding another turntable 53 rotating in the same direction and speed as the turntable 18 and supported by a beam 54 I can mount cops 56 and eyelets 57 to apply one or more strands 58 over the strands 11.

65 The surface 41 which establishes a fixed "break" distance of the strands from the core and a surface upon which they cross over each other, comprises an essential feature of my invention and this feature is applicable also in braiding machines of otherwise conventional construction in which the cops or other supplies of strand are passed in maypole fashion, around each other or in which the strands are deflected around alternate cops.

70

I claim:

1. Apparatus for winding a plurality of strands left hand and an additional plurality of strands right hand around an advancing core comprising:

- (A) means advancing said core from a supply thereof,
- (B) first means supporting a first plurality of supply means of said strands,
- (C) means for rotating said first supporting means left-hand around said core,
- (D) second means supporting a second plurality of supply means of said strands,
- (E) means for rotating said second supporting means right-hand around said core,
- (F) an annular member comprising an outer surface in a circle normal to the axis of advance of said core,
- (G) guide means mounted upstream of said member for said strands,
- (H) means synchronizing said advancing means and said rotating means in a ratio such that each of said

strands rides on said surface at a point between said guide means and said core, a plurality of said strands encountering and passing over another plurality of said strands on said surface.

2. The apparatus of claim 1 wherein said guide for strands rotating in one direction are so mounted as to direct all such strands over all said strands rotating in the opposite direction.

3. The apparatus of claim 1 wherein said guide means are so mounted that, of the strands rotating in one direction, at least one is directed over and at least one is directed under the strands rotating in the opposite direction.
